Patented Mar. 7, 1922.

UNITED STATES PATENT OFFICE.

HIRAM A. BARRETT, OF KNOXVILLE, ILLINOIS.

TANK HEATER.

1,408,682.

Specification of Letters Patent. Patented Mar. 7, 1922.

Application filed February 24, 1921. Serial No. 447,422.

To all whom it may concern:

Be it known that I, HIRAM A. BARRETT, a citizen of the United States, residing at Knoxville, in the county of Knox and State 5 of Illinois, have invented certain new and useful Improvements in Tank Heaters, of which the following is a specification.

This invention relates to means for heating the water in stock-watering tanks and 10 has for its object the provision of simple and inexpensive devices whereby the water will be thoroughly heated and a circulation of the water in the tank set up so that the entire body of water will be raised in temperature 15 and freezing of the same prevented. The present invention relates more particularly to the means for creating a circulation of the body of water in the tank.

The invention is illustrated in the accompanying drawing which shows a perspective view of the improved heater with parts broken away.

The casing of the heater comprises a vertically disposed portion 1 from one side of 25 which extends an offset 2 whereby the casing is given a stepped formation and within the vertically disposed portion 1 is a vertical partition 3 having a slot or notch 4 in its lower edge. A fuel tank or reservoir 5 is 30 supported in any convenient manner within the main body of the casing at that side of the partition 3 more remote from the burners and a feed pipe 6 extends from said tank or reservoir through the slot or notch 4 over 35 the bottom of the casing to a point within the offset or step 2 where it communicates with branches 7 leading to oil burners of any preferred or well-known construction. Around the burners are chimneys or flues 40 8 whereby the flame and heat from the burners are directed against the top of the offset or step 2, as will be readily understood. Over the vertically elongated portion of the casing, I place a cover or lid 9 which has a 45 horizontal plate 10 resting directly upon the top of the casing and provided with perforations 11 therethrough to permit the air to enter and leave the casing without acquiring such a strong draft as will tend to extinguish 50 the flames at the burners. In the ends of the lid or cover are shown openings 12 which further serve to break up the air currents while permitting the entrance of sufficient air to support combustion but the entire ends 55 of the cover may be open if preferred.

Resting upon and extending across the top of the step or offset 2 is a water jacket 13 which may conveniently be constructed of sheet metal and has a depending wing or branch 14 at each end. The said jacket will 60 preferably be of the same width as the offset or step so that one side of the jacket will bear directly against the vertical wall of the main portion 1 of the casing and be closed by the same. The opposite side of the jacket is 65 open, as shown at 15, and the lower end of each depending wing or branch 14 is open, as shown at 16, and disposed at a substantial distance below the top of the offset so as to be accessible to the water in the lower portion 70 of the tank. It will be readily noted that the jacket provides a flue extending upwardly at each side of the offset and across the top of the same through which the water in the tank may circulate. The contacting 75 portions of the offset and the water tank may be welded to prevent displacement of the water back.

In using the device, the entire heater is placed in the tank so as to rest upon the bottom of the same and the water level should be above the offset but below the cover or lid 9. By removing the cover and shifting the partition 3 close to the reservoir or tank 5, access may be had to the burners so as to 80 ignite the same and the partition may then be returned to its normal position closer to the offset than to the tank. The cover may then be replaced and the device will operate without any further attention as long as a 85 supply of fuel remains within the reservoir. The heat from the burners playing directly upon the top of the offset will quickly raise the temperature thereof to a high degree and will, consequently, heat the water contained 90 between the said top and the top plate of the jacket 13. This water, of course, will flow out through the open side 15 of the jacket and will be replaced by cooler water rising through the end branches or wings 14 of the 100 jacket which in turn will be heated and flow out through the opening 15. It will thus be seen that a circulation is set up within the tank so that the entire body of water will be drawn through the jacket and exposed to 105 the heating agent and freezing of the water will be thereby prevented. The device is exceedingly simple in its construction and may be readily produced and applied at a low cost. The heat developed within the casing 110

will play upon the sides of the same and will thus act directly upon the body of water within the tank so that the desired temperature of the water may be economically maintained. After the fuel is ignited at the burners, the hot air will be deflected by the top of the offset of the casing and will flow to the space between the same and the partition 3 and will rise through said space and escape 10 through the openings in the cover while cooler air will be drawn in through other openings and pass down through the space containing the reservoir and thence through 15 the slot or notch 4 to feed the burners as fully set forth in an application executed by me January 29, 1921. The device may be made in any desired proportions so that it may be used in a tank of any size.

Having thus described the invention, what 20 is claimed as new is:

1. In a tank heater, the combination of a casing, a heater disposed within the casing, and a water jacket extending transversely

over the casing and having a central portion resting upon the casing directly over the 25 heater and depending end branches fitting close against the sides of the casing, the said branches being provided with inlet openings at their lower ends and the central portion of the jacket being provided with an outlet 30 opening.

2. In a tank heater, the combination of a casing having a stepped formation, a heater disposed within the casing to play upon the top of the step thereof, and an inverted U-shaped shallow water jacket resting upon the top of the step and bearing closely against the sides thereof, the intermediate portion of said jacket being open at its front side and the ends of said jacket being open at their 35 lower extremities, the top wall and outer end walls of said jacket being parallel with the adjacent surfaces of the casing.

In testimony whereof I affix my signature.

HIRAM A. BARRETT. [L. s.]
